UNITED STATES PATENT OFFICE.

ALEXANDER W. MCARTHUR, OF PHILADELPHIA, PENNSYLVANIA.

ADVERTISING DEVICE.

SPECIFICATION forming part of Letters Patent No. 651,553, dated June 12, 1900.

Application filed July 25, 1899. Serial No. 725,037. (No model.)

To all whom it may concern:

Be it known that I, ALEXANDER W. MCARTHUR, a citizen of the United States of America, and a resident of the city and county 5 of Philadelphia, State of Pennsylvania, have invented certain new and useful Improvements in Advertising Devices, of which the following is a specification.

My invention has reference to advertising 10 devices; and it consists of certain features fully set forth in the following specification and accompanying drawings, forming part thereof.

The object of my invention is to provide a 15 portable advertising device adapted to be moved over streets and to have numerous cards of different advertising firms exposed to view.

It consists of a cylinder rotatably supported 20 on a frame and mounted on wheels. These wheels are arranged in the manner of a tricycle. There is a mechanical connection between the shaft carrying the wheels of the tricycle and the cylinder aforementioned.

25 Air-engaging fans are carried by the cylinder, whereby the force of the wind can communicate motion to the wheels, and of course motion is communicated reciprocally to the cylinder by the rider of the tricycle through 30 the mechanical connection referred to.

In the drawings like parts are referred to by characters of a corresponding kind in the different views.

Figure 1 is a general plan of the device 35 with the tricycle-seat removed. Fig. 2 is a side elevation on a somewhat-reduced scale. Fig. 3 is a section on line A A of Fig. 1.

A is the cylinder. This cylinder in practice can be of a varying size adapted to the 40 different specific needs to which it could be put as a carrier for advertising-cards.

B is an annular track. (Shown in Figs. 1 and 3.) This track is supported on the wheels a a through the frame f f f. These members 45 keep the said annular track in correct annular shape. There may be more braces called for in practice than the drawings show; but this is not material to my invention.

C is an axle carrying the two rear wheels 50 a a. This axle is journaled into the frame B at C C.

D is a primary bevel-gear carried by the

axle C, and E is a bevel-follower fixed to the shaft F. G is a pinion carried by the said shaft.

The frame h h is carried by the fork and steering-post of the front wheel, and the frame f f f is supported to the frame h h by the bars f' f'.

K K are teeth cut on the lower edge of the 60 cylinder A. The teeth of the pinion G mesh with the teeth of the said cylinder.

H H H are a series of rollers carried by the cylinder A. These rollers run on the annular track B. It will thus be seen that the 65 sole support is the said rollers.

b and b are the foot-treads for the operator of the tricycle.

The handle-bar and other features of a tricycle are so well known that it is not thought 70 necessary to make further reference to them here.

m m m m m m m, &c., are a series of air vanes or wings. They are pivoted externally to the perimeter of the cylinder, as shown 75 in Figs. 1 and 2. In the drawings I show these wings located at the upper portion of the cylinder. I of course do not confine myself to this location of the wings. In fact I do not confine myself to any specific location 80 of them on the outer surface of the cylinder. It is sufficient that they are so located. Each of the wings m carries an integral lug n. This lug consists of a light extension, and when the fans are radially extended, as shown 85 in the lower portion of Fig. 1, is adapted to contact with the body of the cylinder, and while the wind acts on the fans, as shown by arrow 3, Fig. 1, the said fan will maintain 90 this position by reason of the said lug thus contacting, as is evident. When the wind, however, acts on the fans, as shown by arrow 1, the fans hug the surface of the cylinder, as shown in the upper portion of Fig. 1.

O' represents the radius of the extended fans 95 and O the radius of the contracted ones. As the device moves forward or in the direction of the arrow 4, Fig. 1, the air striking the fans m m m, &c., in the manner already described will have the effect of rotating the cylinder A in the direction of the arrow 2, Fig. 1. Now the teeth K of the rotating cylinder communicate motion to the shaft F, and this shaft F transmits this motion to the shaft

C through the bevels E and D. It therefore follows that the force of the wind in actuating the cylinder in the manner described will assist the rider of the tricycle in his mission of propulsion.

In practice I would use wind-braces, so as to prevent the tilting of the cylinder. I, however, do not show such in the drawings.

The spaces marked "No. 1," "No. 2," "No. 3," and "No. 4," &c., indicate spaces for the placing of advertisements. These, of course, extend all around the cylinder.

While in the drawings I show the connection between the axle and the cylinder as a geared one, yet I desire it understood that in practice I do not limit myself to this specific arrangement. I could use a friction connection with almost equal success. I therefore do not limit myself to the specific structure set out, but could make modifications without departing from the spirit of my invention.

Having now described my invention, what

I claim as new, and desire to secure by Letters Patent, is—

The combination in an advertising device of a card-carrying cylinder, air-vanes adapted to be expanded or contracted automatically by wind action carried by the cylinder, a track-forming frame, rollers carried by the cylinder and adapted to run on the frame, thus supporting the cylinder thereon, traction-wheels for supporting said frame, a foot-tread with proper connections for actuating said wheels, an axle to which said wheels are affixed, a mechanical connection between said wheel-axle and said cylinder, whereby on the operation of said traction-wheels in the function of locomotion the said cylinder is rotated.

Signed by me at Philadelphia, Pennsylvania, this 28th day of June, 1899.

ALEXANDER W. MCARTHUR.
